FLUORESCENT LIGHTING FIXTURE HAVING
REMOVABLE LIGHT-CONTROLLING PAN-
ELS AT THE SIDES THEREOFRobert G. Marchisio, Wenham, Mass., assignor
to Sylvania Electric Products Inc., Salem, Mass.,
a corporation of Massachusetts

Application February 28, 1950, Serial No. 146,672

2 Claims. (Cl. 240—51.11)

1

This invention relates to electric lighting fixtures and more particularly to those in which elongated linear light sources such as fluorescent lamps are employed.

An object of this invention is to provide an improved means for mounting light-controlling panels in said fixtures.

Another object is to provide an improved means for securing the mounted light-controlling panels in said fixtures.

A further object is to provide mounting and securing means for light-controlling panels which may be quickly and easily disengaged without the use of tools, for maintenance purposes such as re-lamping for example.

Further objects, advantages and features will be apparent from the following description when read in conjunction with the accompanying drawing in which:

Figure 1 is a top plan view of a fluorescent lamp fixture with which the mounting and securing means of this invention may be employed.

Figure 2 is a side elevational view of the fixture of Figure 1.

Figure 3 is a transverse sectional view taken along the line 3—3 of Figure 1.

Figure 4 is an enlarged fragmentary perspective view of an end of the fixture of Figure 1 with the light-controlling panel removed.

Figure 5 is an enlarged fragmentary perspective view of an end of the fixture of Figure 1 with the light-controlling panel in position.

This invention embodies the idea of providing simple, effective mechanisms for mounting and securing light-controlling panels in the sides of fluorescent lamp fixtures. More specifically, it embodies the idea of providing each fixture end-plate with two pairs of retaining tabs on which the light-controlling panels are hung and a latch associated with each pair of retaining tabs for securing the light-controlling panels in position. Figures 1, 2 and 3 of the drawing show one type of fluorescent lamp fixture with which the mounting and securing means of this invention may be employed. Their ready adaptability to fixtures other than the one illustrated will be apparent to those skilled in the art.

The fixture, as illustrated in Figures 1, 2 and 3, comprises an elongated channel-like chassis 1, a pair of end-plates 2 attached to the ends thereof, a V-shaped reflector 3 supported by the end plates 2 and disposed beneath the chassis 1, a plurality of louver fins 4 connected to and extending transversely of the reflector 3, and a pair

of light-controlling panels 5 supported by and extending between the end plates 2.

The elongated channel-like chassis 1 serves as a mounting member to which a ballast and conventional wiring equipment (not shown) may be attached. The top of the chassis 1 is provided with a plurality of knock-outs (not shown) through which suitable mechanical connections may be made to hang or mount the fixture and 10 through which the wiring equipment may be connected to a source of electric power. A pair of lampholders 6 may be mounted on the inside face of the chassis 1 at each end thereof and project outwardly therefrom through suitable cut-outs therefor. Alternatively the lampholders may be mounted on the end plates 2. Fluorescent lamps 12 are supported by these lampholders 6. The end plates 2 are attached to the chassis 1 by means of screws 11 which extend through the 20 chassis and an inwardly turned flange 8 on the upper peripheral edge of each end plate; and by means of a pair of lances 9, in the inside face of each end plate, which interlock in slots cut in the sides of the chassis adjacent the ends thereof.

The reflector 3, which is disposed beneath the chassis 1 and which extends from one end plate to another, is supported by spring latches 13, mounted on the inside face of each end plate and 30 engaged by cooperating slots cut in the ends of the reflector. The reflector 3 has a plurality of slots cut transversely therein into which the louver fins 4 are inserted. Each fin 4 has a tab 14 formed integral therewith which is deformed 35 after the fin has been positioned in the reflector slot, thereby providing a mechanical locking of the fin to the reflector (Figs. 3, 4 and 5).

A pair of reflector chain retainers 18 (Fig. 3), one end of each of which is attached to the chassis 1 and the other end of each to the tab 14 of a louver fin 4, are provided intermediate the ends of the chassis.

These retainers 18 serve as a means for supporting the reflector 3 a few inches below the 45 chassis 1 after the reflector 3 has been disengaged from the spring latches 13. This device provides a convenient mechanism for supporting the reflector when access to the chassis 1 for maintenance purposes is desired. This device also serves as a safety hanger in case of malfunction of spring latches 13.

The manner in which the light-controlling panels 5 are mounted and secured in position is shown in Figures 3, 4 and 5. The inside face of 55 each end plate is provided with two pairs of re-

taining tabs 15, the adjacent faces of each tab defining a slot 7. One of the longitudinal edges of each panel 5 is bent back on itself to define a rib 20. Each panel 5 is positioned on the fixture by inserting the rib 20 into the slots 7 defined by the adjacent faces of the retaining tabs 15 opposite one another on the two end plates. A latch 17 is pivotally mounted on each end plate adjacent each pair of retaining tabs 15. After the panels 5 have been mounted on the retaining tabs 15 the latches 17 are rotated to the closed position as shown in Figures 3 and 5, thereby locking the panels 5 in position. Locking of the panels prevents them from being dislodged or rattling in installations where high vibration is prevalent.

In cases where the panel mounting and locking means of this invention as just described is employed with fluorescent lighting fixtures of the louvered type, such as the fixture of Figures 1, 2 and 3 for example, additional rigidity of the panel mounting may be obtained by providing the lower longitudinal edge of the panel with a rib 21 and the ends of the louver fins 4 with a hook portion 16 in which the rib 21 is seated.

Many highly desirable advantages are obtained by the use of the panel mounting and locking means of this invention. For example, no tools are required to either mount or lock the panels in position. This not only facilitates the original assembly of the fixture but it also greatly simplifies the maintenance problem. No tools are required to remove the panels for cleaning purposes or to provide access to the lamps for re-lamping.

What I claim is:

1. In a lighting fixture, the combination of a chassis; end plates mounted on the ends of said chassis; a reflector lying beneath said chassis and mounted on said end plates; a plurality of louver fins attached to said reflector and extending transversely thereof, the ends of said louver

fins being provided with an upwardly turned hook portion; a projection on each side of the inside face of each of said end plates and adjacent the top thereof; and a light-controlling panel having an inwardly turned rib formed in the upper longitudinal edge thereof and mounted on said projections, the lower longitudinal edge of said panel being seated in the hook portion of said louver fins.

- 10 2. In a lighting fixture, the combination of a chassis; end plates mounted on the ends of said chassis; a reflector lying beneath said chassis and mounted on said end plates; a plurality of louver fins attached to said reflector and ex-
15 tending transversely thereof, the ends of said louver fins being provided with an upwardly turned hook portion; a projection on each side of the inside face of each of said end plates and adjacent the top thereof; a light-controlling
20 panel having an inwardly turned rib formed in the upper longitudinal edge thereof and mounted on said projections, the lower longitudinal edge of said panel being seated in the hook portion of said louver fins; and a latch mounted on the
25 inside face of each end plate adjacent each of said projections and movable into locking engagement with said light-controlling panel.
